COMPOSITE BEAM

Rolf K. O. Sahlberg, New York, N. Y.

Application November 18, 1935, Serial No. 50,422

5 Claims. (Cl. 72—110)

My invention relates to a beam construction comprising a rolled or otherwise fabricated steel beam acting conjointly with a concrete or other slab resting upon and bonded to the beam with sufficient rigidity as to restrain the horizontal shear stresses developed from the load. Said slab together with the steel area above the neutral axis forms the zone of compression of the composite beam. More specifically my invention relates to a beam construction in which the slab constitutes the floor when the composite members are spaced in accordance with load and span.

Although my improved composite beam preferably uses a concrete slab carried by the beam it may be utilized with slabs, planks or plates of other materials capable of restraining compressive stresses. Therefore, when concrete slabs are referred to in the following description and claims I intend to be limited to that particular material only when such limitation is clearly stated.

Floor constructions having steel beams as load bearing members and a concrete or other slab transmitting the load to such beams are at the present time so designed that the stresses in the steel beams shall balance the bending moment without any helpful effect from the slab between the beams. No helpful effect can be obtained because heretofore no provision has been made to secure a sufficiently rigid connection between the beams and the slabs as is the case with my improved composite beam.

By sufficiently and effectively bonding the concrete slab to the steel beam so that the slab will be forced to deform in the same proportion as the top flange, as will be explained, considerable saving in steel can be obtained. In this way the zone of compression will be composed of the steel area above the neutral axis of the composite beam in addition to the area of the concrete slab between the steel beams as compared to the steel area alone as with present constructions.

The main object of my improved composite beam is to provide a construction in which will be developed a connection between the concrete slab and the top part of the steel beam, said connection having sufficient rigidity as to withstand the horizontal shear developed under the load.

In order that my invention may be better understood attention is directed to the accompanying drawing forming a part hereof and in which

Figure 1 is a side view of my improved composite beam in its preferred construction.

Figures 2, 4, and 6 are detail views on somewhat larger scale illustrating different forms of con-

necting members between the concrete slab and the beam.

Figures 3, 5, and 7 are plan views in detail showing the connections illustrated in Figures 2, 4, and 6 respectively and

Figure 8 is a stress diagram indicating the distribution of stresses in the connection shown specifically in Figures 6 and 7.

The composite beam shown in Figure 1 is illustrated as a fabricated steel beam with upper chord 1, lower chord 2, a concrete slab 3, diagonals in tension 4, diagonals in compression 5 and anchors 6. The anchors shown in Figure 1 correspond with the anchors illustrated in Figures 4 and 5 but other forms of anchors may be employed as in Figures 2 and 3 or Figures 6 and 7 or their equivalent.

The fabricated beam shown in Figure 1, omitting the anchors and concrete slab, is of well known form, the top and bottom chords being composed of angle irons with their vertical webs separated a short distance for the reception of the tension and compression members 4 and 5 which are welded or otherwise rigidly secured to the angles. Other forms of fabricated beams may be employed instead of the specific construction illustrated in the drawing.

The anchors 6 are carried upon the upper chord of the beam and are preferably secured in place by connections between the web system and the upper chord, as in Figures 2 to 5 inclusive. In order to obtain a rigid connection between the slab 3 and the steel beam it is necessary to develop an anchoring member 6 capable of resisting the horizontal shear stresses without permitting any movement in the surface between the slab 3 and the upper chord 1. In its simplest form each anchoring member consists of an inverted T-section with the horizontal flange 8 welded or otherwise rigidly secured to the top of the steel beam as indicated in Figures 6 and 7. The shear stresses are here transmitted through the surface pressure between the vertical flange 7, and the concrete slab to the steel beam and the vertical flange 7 must have a section modulus of sufficient magnitude to resist the developed bending movement.

Figure 8 shows a pressure diagram based for purposes of illustration upon the form of anchor shown in Figure 6. This diagram is governed by various causes and the shape of the same therefore varies somewhat by reason of these causes. However, it may be stated that the rectangular pressure diagram 9 is the maximum and a triangular diagram 10 is the minimum

and that the actual diagram 11 is a parabolic diagram between the maximum and minimum diagrams. The resultant P of the stresses passes through the center of gravity of the diagram 11 and its distance a from the top of the steel beam is somewhere between one-half and one-third of the height of the vertical flange 7 measured from the bottom of the diagram. The section modulus of the vertical flange must be sufficient to resist the moment $P \times a$. The horizontal flange 8 is connected to the top of the steel beam in such a manner that it resists the horizontal force P and a force couple P', acting in opposite directions and at a distance b from each other balancing the moment $P \times a$.

Furthermore, the connection must be developed so as to give a minimum moment in the top chord. This result is accomplished if the resultant P from the pressure diagram coincides with the crossing point 12 of the extended center lines of the diagonals 4 and 5 as indicated by dash and dot lines in Figure 8. If in some cases this ideal condition cannot be fully realized a certain amount of bending moment may be allowed safely without overstressing the top chord by reason of the fact that in the center of the span (where the stresses in the top chord are a maximum) the horizontal shear stresses are zero, and at the support (where the shear is a maximum) the stresses from bending moment are zero. The area of the pressure surface 7 is determined by the magnitude of shear stresses.

The anchoring members 6 shown in Figures 2, 3 and 4, 5 are also designed in accordance with the above principles. In the former figures the vertical member 7 is slightly curved and is supported along two parallel edges 13 and 14, the edge 13 being rigidly connected to the steel beam by the member 17 which may be welded or otherwise secured to the tension diagonals 4. In Figures 4 and 5 each anchor is provided with one horizontal edge 15 and one vertical edge 16, the latter being the vertical part of a tongue 18 welded or otherwise secured to the compression diagonals 5.

As stated, the anchoring members 6 are secured to the steel beam preferably by welding or in any other way by which a rigid connection is secured. From what has been said it will be noticed that the member 6 can be secured either to the top chord 1, or to the web system 4 and 5 or to the top chord and compression members or to the top chord and the tension members, of the web system.

With the arrangement of the composite beam above described I make use of the concrete or other slab as part of the zone in compression for resisting bending moment. By doing this a considerable saving in steel is effected because the steel area in the top flange may be designed to carry only the weight of the concrete slab and the weight of the steel beam.

In consequence the saving of steel in this part of my improved composite beam as compared to beams heretofore proposed is in the same proportion that the weight of the concrete slab and steel beam is to the total load.

An additional saving of steel in the bottom beam is obtained by reason of the fact that the level arm between the tension member and the neutral axis of my improved composite beam is considerably greater in percentage than with 10 beams heretofore proposed. The saving of steel in the bottom flange is in proportion to these level arms.

My improved beams comprising the top and bottom flanges with a connecting web are preferably manufactured so as to be provided with a slight camber. By this I mean that the beam is slightly curved and when placed on the job the apex of the curve extends upward. This pre-camber is very small, being of the order of a 20 fraction of an inch, and is so chosen that the weight of the concrete slab and beam will develop a deflection of the steel beam equal to the pre-camber. In this way the steel beam will be straight and even, when the concrete slab has 25 hardened.

It is understood that the form of my invention shown and described are merely representative and that various changes in the shape and arrangement of parts may be resorted to without departing from the spirit of my invention and the scope of the claims hereafter presented.

Having now described my invention what I claim as new therein and desire to secure by Letters Patent is as follows:

1. An improved composite beam supported at its ends and comprising a steel beam with upper and lower chord members and an intermediate lattice web, a slab carried by the beam for resisting compressive stresses and anchoring members for anchoring the slab to the beam, said anchoring members being rigidly secured to the upper chord with such rigidity that the slab, in cooperation with the upper chord, will form the zone in compression of the composite beam and each anchoring member having a pressure member supported along a plurality of edges.

2. An improved composite beam as recited in claim 1 said anchoring member being supported along two horizontal edges in the same levels.

3. An improved composite beam as recited in claim 1 said anchoring member having a pressure member supported along one horizontal and one vertical edge.

4. An improved composite beam as recited in claim 1 said anchoring member having a straight pressure member.

5. An improved composite beam as recited in claim 1 said anchoring member having a curved pressure member.
